(57) **CLAIM**

The ornamental design for lighted screwdriver, as shown and described.

DESCRIPTION

FIG. 1 is a top right perspective view of a lighted screwdriver showing the present design;

FIG. 2 is a right elevational view thereof;

FIG. 3 is a bottom plan view thereof;

FIG. 4 is a left elevational view thereof;

FIG. 5 is a top plan view thereof;

FIG. 6 is a front elevational view thereof; and,

FIG. 7 is a rear elevational view thereof, the broken circular line showing a recessed portion of the lighted screwdriver that forms no part of the claim.

Other broken lines in the drawings showing a tool bit are illustrative of environment and form no part of the claim.

1 Claim, 3 Drawing Sheets

FIG. 7

FIG. 6

FIG. 2

FIG. 3

FIG. 4

FIG. 5
